UNITED STATES PATENT OFFICE.

HENRY K. WEBSTER, OF MADISONVILLE, KENTUCKY.

SAFETY DEVICE.

Application filed May 28, 1923. Serial No. 642,079.

To all whom it may concern:

Be it known that I, HENRY K. WEBSTER, a citizen of the United States, residing at Madisonville, in the county of Hopkins and 5 State of Kentucky, have invented new and useful Improvements in Safety Devices, of which the following is a specification.

This invention relates to a safety device for elevators, the general object of the 10 invention being to provide means for preventing the elevator from dropping if the hoisting cable should break.

This invention also consists in certain other features of construction and in the 15 combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is an elevation showing an elevator equipped with my invention.

Figure 2 is a section on line 2—2 of Figure 1.

30 Figure 3 is a section on line 3—3 of Figure 2.

Figure 4 is a view showing the position of the parts when the cable breaks.

Figures 5 and 6 are detail views.

In these views 1 indicates the elevator 35 cage and 2 indicates the guideways for the same. 3 indicates the cross bar which engages the guideways and which is connected with the cage by the rods 4. A second cross bar 5 is arranged below the bar 3 and this 40 bar 5 has its ends engaging the guideways. A pair of dogs 6 are pivoted to the bar 5 and a spring 7 fastened to the upper part of the dogs tends to throw their pointed lower ends outwardly against the guides and

thus prevent downward movement of the 45 cage. The upper ends of the dogs are connected by the links 8 with the hoisting cable 9 and rollers 10 on the bar 3 engage the dogs.

From the foregoing it will be seen that 50 the weight of the parts on the cable will hold the ends of the dogs out of engagement with the guideways so that the cage has free movement but if the cable should break the spring 7 will pull the upper ends 55 of the dogs together and thus throw their lower ends into engagement with the guideways so that the cage is brought to rest and cannot fall. The weight of the cage will tend to cause the dogs to grip the guideways 60 so that the greater the load the greater the grip the dogs will have upon the guideways.

It is thought from the foregoing description that the advantages and novel features 65 of my invention will be readily apparent.

I desire it to be understood that I may make changes in the construction and in the combination and arrangement of the several parts, provided that such changes fall within the scope of the appended claim.

What I claim is:—

A safety device for elevators comprising a cross bar connected with the top of the elevator and engaging the guideways, a second cross bar below the first and engaging 75 the guideways, dogs pivoted to the second cross bar and having their upper ends extending through the first bar, means for connecting the hoisting cable with the upper ends of the dogs and spring means connecting the upper ends of the dogs together and acting to throw their lower ends into engagement with parts of the elevator shaft if the cable should break and rollers on the first cross bar for acting as stops for limiting the movement of the dogs.

In testimony whereof I affix my signature.

HENRY K. WEBSTER.
